UNITED STATES PATENT OFFICE.

ARTHUR JOHN ADAMS, OF HEYWOOD, NEAR WESTBURY, ENGLAND.

SPRINGING OF VEHICLES.

1,332,093.

Patented Feb. 24, 1920.

Application filed December 20, 1917. Serial No. 208,137.

To all whom it may concern:

Be it known that I, ARTHUR JOHN ADAMS, a subject of the King of Great Britain, and resident of The Cottage, Heywood, near 5 Westbury, in the county of Wilts, England, have invented a certain new and useful Improvement in the Springing of Vehicles, of which the following is a specification.

This invention relates to improvements in 10 the springing of road and other vehicles of the kind wherein the vehicle frame is attached to the axle by means of bell-crank levers arranged in pairs, the members of each pair being pivotally connected together, and wherein a spring is provided 15 to resist relative movement of these levers about their pivotal connection, such as is described in the specification of an application for Letters Patent of even date here- 20 with.

According to this invention, in order to maintain the thrust plates for the spring in constant alinement, the thrust plate attached to one of the levers is pivotally connected 25 thereto by eyebolts swinging about an axis which passes through the spring transversely to the axis of the latter. The pivots on which the said eyebolts turn are constructed similarly to the knife edge bearings for the 30 beams of weighing scales or balances, so that there is a rolling instead of a rotary contact between these parts whereby efficient working of the springing construction will not be prevented by rust and the neces- 35 sity for lubrication is avoided. The eyebolt pivots are carried by a yoke which is formed as an extension of the cap holding one of the levers on the axle casing of the vehicle to which the improved springing 40 is fitted.

Preferably, the bushes at the extremities of the levers, through which the pins attaching the levers to the vehicle frame are passed, are made of a barrel-shape so that 45 they can rock in the eyes at the ends of the levers and are therefore self-aligning, thus preventing the transmission of any lateral bending stress to these levers.

The improved method of springing is applicable to both the front and the rear axle 50 springs of vehicles, and the main lever, *i. e.* the one attached to the axle casing, may extend forwardly or backwardly as required by the construction of the vehicle frame. In 55 the case of either a front axle or a rear

axle spring, the main lever on one side may be fixed to the axle casing, *e. g.* by a key, so as to form a torque rod for the axle, or the levers on both sides may be free if a separate torque rod is provided. When one 60 of the main levers on a rear axle also serves as a torque rod, the levers on this axle are preferably arranged so that they extend forwardly.

The accompanying drawing shows how 65 the said invention may be conveniently and advantageously carried into practice.

In this drawing:

Figure 1 is a side view, and

Fig. 2 an underside view of an axle 70 springing constructed according to this invention.

Fig. 3 is an end view thereof, looking from the left of Fig. 1.

Figs. 4 and 5 are detail views, on an en- 75 larged scale, hereinafter described.

Fig. 6 is a detail view illustrating a modification hereinafter described.

As shown, *a, b* are levers of the bell-crank type of different lengths attached to the 80 vehicle frame by eyes *c, c* and pivotally connected together at *d*. An arm *e* of the lever *b* has a thrust plate *f* pivotally connected thereto by an eyebolt *g* with a screw-threaded shank *g'* along which a nut *h* with 85 a boss *i* is adjustable to tension the spring by varying the position of the plate *f* which is carried on the said boss *i*.

The lever *a* is provided with a cap *j* by which it is secured to the axle casing, and 90 this cap has a yoke *k* formed integrally therewith. As shown in Fig. 4, each arm of this yoke supports a pivot pin *l* having a knife edge *m* formed thereon. Eyebolts *n, n* bearing against this knife edge *m* carry 95 a second thrust plate *o*, and a spring *p* is held between these thrust plates. Thin washers *n'* of a non-corrodible material are provided at the sides of the eyebolts *n* to prevent locking or setting of these parts 100 by rust.

Relative movement between the levers *a, b* about the pivot pin *d* when a load is applied to the eye *c, c*, is resisted by this spring as will be readily understood, and 105 when any such movement takes place the pivotal mounting of the eyebolts *g* and *n, n* preserves the alinement of the thrust plates *f* and *o*.

In Fig. 1, the cap *j* is shown fitted with 110

a feather or key *s* to secure the lever *a* to the axle casing when this lever is used as a torque rod.

The eyes *c*, *c* are fitted with barrel-shaped bushes *g*, as shown in section in Fig. 5, held in the eyes by set screws *r*, this arrangement permitting these bushes to adjust themselves into alinement with the pins by which the levers *a*, *b* are attached to the 10 vehicle frame.

An alternative form of the lever *b* is illustrated by Fig. 6, in which the arm *e'*, corresponding to the arm *e* of Fig. 1 is formed with a ball *t* at the end thereof, 15 and the corresponding thrust plate *f'* is formed with a socket *u* receiving this ball. Adjustment between the plates *f'* and *o* is effected by means of the nuts *v* on the eyebolts *n*.

20 What I claim is:—

1. A springing for vehicles comprising in combination two levers arranged end to end, a single pivotal joint connecting the said levers at their adjacent ends one to the other, means for connecting the said levers to a vehicle frame at their remote ends, means carried by one only of the said levers for attaching this lever to an axle casing, said axle casing lying in a vertical plane 25 parallel to the plane in which is situated said single pivotal joint, an arm projecting from one of said levers, a yoke projecting from the other of said levers, and a spring interposed between said arm and said yoke projecting respectively from the said levers.

2. A springing for vehicles comprising in combination two levers arranged end to end, a single pivotal joint connecting the said levers at their adjacent ends one to the other, means for connecting the remote ends of the said levers to a vehicle frame, means carried by one only of the said levers for attaching this lever to an axle casing, an arm and a yoke projecting respectively 40 from the said levers, thrust plates pivotally connected to the said arm and yoke respectively, and a spring between the said thrust plates.

3. A springing for vehicles comprising in combination two levers arranged end to end, a single pivotal joint connecting the said levers at their adjacent ends one to the other, means for connecting the said levers to a vehicle frame at their remote 50 ends, means carried by one only of the said levers for attaching this lever to an axle casing, said axle casing lying in a vertical plane parallel to the plane in which is situated said single pivotal joint, an arm pro-

jecting from one of the levers, an eyebolt 60 pivotally connected thereto, a nut adjustable along the eyebolt, a thrust plate supported by the said nut, a second thrust plate pivotally connected to the other of said levers, and a spring between the said thrust 65 plates.

4. A springing for vehicles comprising in combination two levers arranged end to end, a single pivotal joint connecting the said levers at their adjacent ends one to the other, means for connecting the said levers to a vehicle frame at their remote ends, a detachable cap securing one of the said levers to an axle casing, a yoke extending from the said cap, a thrust plate carried by 75 the said yoke, a second thrust plate carried by the other one of the said levers, and a a spring between the said thrust plates.

5. A springing for vehicles comprising in combination two levers arranged end to end, a single pivotal joint connecting the said levers at their adjacent ends one to the other, means for connecting the said levers to a vehicle frame at their remote ends, a detachable cap securing one of the said levers to an axle casing, a yoke extending from the said cap, pivot pins supported by 85 the arms of the yoke, eyebolts bearing against said pins, a thrust plate carried by the other one of the said levers, and a spring 90 arranged between the said thrust plates.

6. A springing for vehicles comprising in combination two levers arranged end to end, a single pivotal joint connecting the said levers at their adjacent ends one to the other, means for connecting the said levers to a vehicle frame at their remote ends, an arm carried by one of said levers, a yoke carried by the other lever, a spring interposed between the arm and the yoke, and 95 means for attaching one of said levers to an axle casing, said axle casing lying in a vertical plane parallel to the plane in which is situated said single pivotal joint.

7. A springing for vehicles comprising in combination two levers arranged end to end, a single pivotal joint connecting the said levers at their adjacent ends one to the other, means for connecting the said levers to a vehicle frame at their remote ends, an arm carried by one of said levers, a yoke carried by the other lever, and adapted to 110 form an attaching means for securing the said other lever to an axle casing, and a spring interposed between the arm and the 115 yoke.

ARTHUR JOHN ADAMS.
